UNITED STATES PATENT OFFICE.

CHARLES M. GILBERT, OF MINNEAPOLIS, MINNESOTA.

BRAN-DUSTER.

SPECIFICATION forming part of Letters Patent No. 373,453, dated November 22, 1887.

Application filed December 9, 1886. Serial No. 221,230. (No model.)

To all whom it may concern:

Be it known that I, CHARLES M. GILBERT, a citizen of the United States, residing at Minneapolis, in the county of Hennepin and State of Minnesota, have invented certain new and useful Improvements in Bran-Dusters, of which the following is a specification.

My invention relates, mainly, to improvement of the devices for freeing bran-duster screens of adherent dust and flour, as will be hereinafter more fully set forth.

My improvements are illustrated in the accompanying drawings, in which—

Figure 1 is a central sectional elevation of the machine containing the improvements, the dusting-case being shown in the position of its highest vertical movement. Fig. 2 is a detached view of the upper bridge-tree. Fig. 3 is a detail of the cam-bearing spider. Fig. 4 is a central section of the same on the line *xx* of Fig. 3. Fig. 5 is a detached view of the intermediate bridge tree, showing the channel in which the cams of the spider travel; and Fig. 6 is a sectional view of a portion of the same on the irregular line *yy* of Fig. 5. Fig. 7 is a top view of a portion of the head of the machine-housing, the dusting-case head, the circular rack, its pinion, and the ring and packing within the rack. Fig. 8 is a transverse section of a portion of the same on the line *ww* of Fig. 7. Fig. 9 is a plan view of the lower head of the dusting-case, and of the ring and packing surrounding it. Fig. 10 is a transverse section of the same on the line *zz* of Fig. 9; and Fig. 11 the same as Fig. 10, but showing the dusting-case head at the limit of its downward reciprocation.

In the drawings, 1 represents the cylindrical case of the machine, supported by legs or other supports, 2. A central vertical shaft, 3, has its lower bearing in a step, 4, in a lighter screw, 5, which is supported by the lower bridge-tree, 6, and has its upper bearing in a bridge-tree, 7, at the head of the machine. This upper bridge-tree is of arched form, with its ends made fast to the top of the machine, and has an oil-chamber, 8, at the center, surrounding the shaft 3. The driving pulley 9 is near the lower end of the shaft.

Between the arched bridge-tree 7 and the

head 10 of the machine-case is a pinion 11, fixed on the shaft 3, which turns the spur-wheel 12. The hub 13 of the spur-wheel is fast to a spindle, 14, and has its bearing on the box 15, secured to the top of the machine.

On the lower end of the spindle 14 is a pinion, 16, fast thereto, and which meshes with the circular rack 17, which is secured to the disk-head 18 of the dusting-case 19. By these means the dusting-case is slowly revolved.

The bran is fed to the dusting-case through the opening 20 in the cylinder-head, and thence through the opening 21 in the head of the dusting-case, whence it falls upon the revolving disk 22, carried by the shaft 3, and is thrown outward by the action of the disk to the wire-cloth 23 of the dusting-case. Brushes 24, carried by the shaft 3, and which have a rapid motion, sweep the wire-cloth and force the flour and fine particles through the meshes. The bran within the dusting-case, after being subjected to the brush action, falls between the arms of the spider, which constitutes the lower head, 25, and is spouted off through an opening, 26, in the lower head, 27, of the cylinder. The freed flour, falling outside the dusting-case, is discharged from the machine through the opening 28.

The lower head, 25, of the dusting-case has a downwardly-projecting double hub, composed of a larger upper portion, 29, and a smaller lower portion, 30, the latter forming the bearing for the dusting-case and turning in a socket, 31, provided on the intermediate bridge-tree, 32. This hub extends below the lower head, 27, of the central opening, 33. A plate, 34, having a central opening within which the shaft 3 turns loosely, rests upon the dusting-case bottom and prevents bran and dust from falling into the hollow of the hub.

On the cylinder bottom 27 is bolted or otherwise secured a wooden ring, 35, directly beneath the end of the dusting-case, and the inner side of the ring is covered with sheep-skin (with its wool) or other suitable packing, 45. The dusting-case head 25 has an angular circular flange, 36, consisting of an upright portion and a horizontal portion extending outward from the upright portion. The horizontal portion of the flange is bolted to the

screen-frame of the dusting-case, and the upright portion revolves in contact with the packing 45. A ring, 37, is also bolted or attached by screws to the cylinder-head 10 above the dusting-case head 18, and has its outer side covered with sheep-skin or other suitable packing, 45, and the rack 17 revolves with its inner surface in contact with the packing. These rings, with their packing, should be high enough to keep the flange 36 and rack 17 in constant contact with the packing during the longitudinal movements of the dusting-case, and such contact, while permitting free rotary and longitudinal movement of the dusting-case, 15 prevents the passage of air in either direction at those points, and thus prevents the mixing of particles of bran and flour that have been separated by the action of the dusting-case.

To the upper portion, 29, of the hub is attached the spider 38, the arms of which have downwardly-projecting flanges 39, whose under surfaces are inclined lengthwise to form cams for engaging oppositely-inclined surfaces provided on the bridge-tree 32. An annular 25 channel, 40, is formed by the circular flanges 41 on the bridge-tree, and serves as a way for the cams 39 of the spider. The channel 40 may be made tight and kept filled with oil. In the channel are the inclined raised 30 surfaces or cams 42, which are engaged by the revolving cams 39, and cause the spider, and consequently the dusting-case, to be lifted. As the dusting-case rotates slowly, it is gradually raised while the cam-surfaces are in contact, and when the ends of the cams are 35 reached the moving cams drop to the bottom of the channel, and a jar is given the dusting-case by the fall, which frees the cloth of adhering particles. To avoid unnecessary noise 40 and wear of parts, a small cushion, 43, of rubber or other elastic material, is placed beneath the offset of the cams 42, and the bottom of the channel is made to slope to the top of the cushion, as shown at 44, Fig. 6.

45 What I claim, and desire to secure by Letters Patent, is—

1. In a bran-duster, the combination, with

an upright rotating dusting-case, of cams carried by the lower head thereof, a way in which said cams move, and fixed cams therein engaged by the moving cams, substantially as set forth. 50

2. The combination, with a dusting-case constructed with a head having a hub, of a bridge-tree having a socket for said hub, a circular channel provided on said bridge-tree, cams in said channel, a spider attached to said hub, and cams thereon arranged to travel in said channel and engage said fixed cams, substantially as set forth. 55

3. The combination, with the dusting-case constructed with a double hub, 29 and 30, and socket 31, of the spider 38, bearing-cams 39, and the channel 40, provided with cams 42, substantially as set forth. 60

4. The combination, with the lower head, 25, of the dusting-case having the angular flange 36, of the stationary ring 35 on the bottom of the housing and the packing 45 between said flange and ring, for the purpose set forth. 70

5. The combination, with the cylinder-head 10 and dusting case head 18, of the ring 37, secured to the former, the circular rack 17, secured to the latter, and the packing 45 between said ring and rack, substantially as and 75 for the purpose set forth.

6. In a bran-duster, in combination, a housing and its upper and lower heads, a dusting-case and its upper and lower heads, mechanisms for rotating and reciprocating the dusting-case, rings extending inward from the inner surfaces of the housing-heads, rings carried on the dusting case heads concentric with and overlapping said stationary rings, and suitable packing in the annular spaces between the rings, forming therewith dust-tight joints adapted to permit rotary and longitudinal movement of the dusting-case, and to prevent the mixing of material separated by the dusting-case, substantially as set forth. 85
